UNITED STATES PATENT OFFICE

EMANUEL L. FENSTERMAKER, OF LANCASTER, PENNSYLVANIA, ASSIGNOR OF ONE-
THIRD TO FRANKLIN H. BURKHART, OF LANCASTER, PENNSYLVANIA.

SCREW-CAP WRENCH.

1,225,231.

Specification of Letters Patent.

Patented May 8, 1917.

Application filed March 1, 1915. Serial No. 11,294.

To all whom it may concern:

Be it known that I, EMANUEL L. FENSTERMAKER, a citizen of the United States, residing at Lancaster, Lancaster county, and State of Pennsylvania, have invented and discovered certain new and useful Improvements in Screw-Cap Wrenches, of which the following is a specification.

My said invention consists of certain improvements in the construction and arrangement of parts of wrenches for removing screw-caps from the tops of containers, such as fruit jars, cans, etc., whereby such a wrench is provided which is not only very convenient, but can be used without injury to the screw-cap, or container top, and will accomplish the result in an easy and convenient manner, all as will be hereinafter more fully described and claimed.

Referring to the accompanying drawings which are made a part hereof and on which similar reference characters indicate similar parts,

Figure 1 is a plan view of one of my improved wrenches, or screw-cap removing devices, as it appears when in use, being shown on a jar top as when ready for use,

Fig. 2 a section through the tool, as seen when looking in the direction of the arrows from the dotted line 2—2 in Fig. 1,

Fig. 3 a plan view of the other side of the tool from that shown in Fig. 1 and separate from the jar top,

Fig. 4 an edge view of a modified form of the handle, and

Fig. 5 a perspective view of another form of shoe.

In said drawings, the portions marked A represent the handle, and B the shoe or clamping head of the wrench.

The handle A may be cast in one piece and of the form best shown in Fig. 2, or it may be of pressed metal of the form best shown in Fig. 4. Near its inner end it has an offset or shoulder, as at point 10, beyond which an ear 11 extends, to which the shoe B is hinged on a pair of apertured lugs or ears 1 and 2 located at equal distances inset from the respective ends of the shoe, and said shoe also has a pivot 12.

Said shoe B is formed with a concave operating face to fit against the periphery of the jar top, the curvature of the face, which is adapted to impinge against said jar top, corresponding to the curvature thereof. The

edge of said shoe is curved in cross section, whereby it is adapted to fit into the groove formed near the upper edge of said jar top and thus be adapted to operate against said surface without in any manner injuring or 60 distorting said top or the glass within. Said shoe is mounted on the handle A by means of a pivot 12 which extends through the aperture in the lug 1. A loop 13, of a size corresponding to the transverse curvature of the edge of the shoe B, and consisting of one or more strands of wire, is attached to the other lug 2 of said shoe at a point 14, being preferably extended through the perforation at said point and doubled around 70 itself on the outside, as clearly shown in Figs. 1 and 3. Said wire 13 forms a loop of sufficient size to embrace the screw top, and the projecting portion 3 of said shoe B serves as a shoulder-brace for the loop, and 75 also acts as a guard to prevent the loop from slipping off the end of said shoe. The other end of the wire is attached to the handle A at a point 15, adjacent to pivot 12, but a distance therefrom substantially equal 80 to the distance point 14 is from the same pivot. The attachment of the wire to the handle at point 15 is made in substantially the same manner as the attachment to the shoe B at point 14. By reason of pivoting 85 the shoe to the handle at a point near one end of the shoe and attaching the wire 13 to the shoe at a point the same distance from its opposite end, an equal pressure is obtained throughout the entire length of the 90 concave surface of the shoe against the jar top, and any danger of denting or marring the top is obviated. The two end portions 3 and 3^a of the shoe are disposed respectively at equal distances from the apertures in the 95 lugs 1 and 2, and this, with the curved portion of the shoe and the loop 13, forms a substantially circular gripping surface for uniformly engaging with the periphery of the jar cap, i. e. the several gripping elements are all brought into concentric alignment when the lever or handle A is operated. In Fig. 5 I have shown the shoe with a flat face for use to grip on the body of a 100 jar when needed or desired.

The shoe B has the lug and shoulder portions (1 and 2) thereof constructed of the same design and dimensions as the corresponding lug and shoulder portions (3 and 3^a), i. e. the two ends of the shoe are con- 110

structed alike, and by this provision, either end may be pivoted on the pin 12 when the parts are being assembled. Also the position of the shoe may be reversed after the 5 device has been in use and the cap engaging face of the shoe unevenly worn.

In use, the wrench is applied to a screw top as indicated in Fig. 1, and the user, by forcing the handle in the direction indicated 10 by the arrow in Fig. 1, clamps the shoe B against the jar top with its convex edge and the convex surface of the wire 13 engaged in the groove in said top. The pressure upon the handle clamps the wire and shoe firmly 15 to said top and enables the user to obtain sufficient leverage on said top to start it back upon the threads, or, when reversed, to screw it down tightly to secure an air-tight closure. When desired or needed, a second 20 wrench, with shoe of form shown in Fig. 5, may be used to hold the jar. The arrangement of the point of attachment of the wire 14 to one end of the shoe, and the point of fulcrum between the shoe and the handle at 25 the other end, equi-distant from the respective ends, is an important feature of this invention, inasmuch as it insures an even and continuous pressure throughout the entire 30 length of the shoe and avoids forcing one corner or the other into the jar top and thus

injuring the top or destroying its contour. The lines of pressure are indicated by radial dotted lines in Fig. 1.

Having thus fully described my said invention, what I claim as new and desire to 35 secure by Letters Patent, is:

A wrench for removing screw tops comprising a clamping shoe having a curved face formed to fit against the periphery of the screw top upon which the wrench is to operate and having apertures positioned equidistant from the ends thereof with end portions projecting uniformly beyond said apertures, a handle fulcrumed in one of said apertures, and a wire loop secured at one of its ends in the other aperture and at its other end to the handle at a point adjacent to the fulcrum of the shoe, said shoe and the main part of the wire loop being adapted to be brought into circular alinement to uniformly 45 grip the peripheral edge of a screw top, substantially as set forth.

In witness whereof, I have hereunto set my hand and seal at Lancaster, Pennsylvania, this 16th day of February, A. D. nine- 55 teen hundred and fifteen.

EMANUEL L. FENSTERMAKER. [L. S.]
